UNITED STATES PATENT OFFICE.

CREASEY J. WHELLAMS, OF ST. PAUL, MINNESOTA.

WINDOW-SCREEN.

No. 822,227.

Specification of Letters Patent.

Patented May 29, 1906.

Application filed February 13, 1905. Serial No. 245,340.

To all whom it may concern:

Be it known that I, CREASEY J. WHELLAMS, a citizen of the United States, residing at St. Paul, in the county of Ramsey and State of Minnesota, have invented a new and useful 5 Window-Screen, of which the following is a specification.

My invention relates to improvements in window-screens, and has for its object greater 10 durability and effectiveness in use, together with a minimum cost of production and simplicity of construction.

This invention relates more particularly to a metal screen-frame having its parts constructed to hold the screen taut and at the 15 same time forming a strong and rigid frame, which embraces a tongue on the casing.

In the accompanying drawings, forming part of this specification, Figure 1 is a front 20 view of a portion of a window-screen and casing, showing my invention. Fig. 2 is a view looking down on Fig. 1. Fig. 3 is an enlarged sectional view on the line X-X through one of the sides of the frame. Fig. 4 is a plan 25 view of a back section of the corner-pieces. Fig. 5 is a view showing the back sections of the contiguous sides placed in position on the section of the corner-pieces (shown in Fig. 4) when the parts are assembled. Fig. 6 is a 30 view showing the netting on the parts shown in Fig. 5. Fig. 7 is a view showing the front sections of the sides placed upon the parts shown in Fig. 6 to illustrate the method of constructing my invention, and Fig. 8 is a 35 view of an alternate construction.

In the drawings, let A represent a portion of my improved window-screen, which is preferably rectangular in shape, and B a detail portion of the window-casing in which my 40 improved screen is adapted to be placed. The parts of my invention are preferably constructed of metal, the contiguous upper and lower sides C and D being formed by back and front sections 2 and 3. These sections, 45 respectively, have longitudinal ribs 4 and 5, flanges 6 and 7 on their inner edges, and spring-flanges 8 and 9 on their outer edges. A resilient strip of wood or other suitable material 50 is placed between the ribs, and the woven-wire screen 11 is passed between said resilient strip and the rib 5 of the back section 3. Screws 12 are passed through the holes 13 in the sections of the sides and the strip 10 and 55 are fastened on the back of the frame by nuts 14, which rest in the recess formed by the rib

5 in the back section. Rivets may be used in place of these screws, if desired. The back rib of the sections is let into the front rib, and when the parts are fastened together by the screws 12 the screen-netting 11 is clamped 60 between the flanges 6 and 7 and the resilient strip 10 and back rib 5. When the parts are thus secured, the flanges 8 and 9 form a groove 15 between the vertical side sections, in which a tongue 16 on the window-casing 65 passes. This tongue, as shown in Fig. 2, is a metal strip having a flange 17, which is fastened by nails 18 or other suitable means to the vertical side 19 of the window-casing.

The tongue is bent over at 20 and is resilient 70 to form a spring engagement with the flanges 8 and 9 and hold the screen when raised or lowered. One of these parts (the flanges 8 and 9) may be made resilient, and the other (the tongue 16) may be made rigid 75 to effect a spring sliding connection between the screen-frame and the window-casing.

The outer flanges 8 and 9 on the front and back sections of the horizontal sides of the screen-frame impinge when the parts are fastened together, as shown in Fig. 2, and do not 80 form a groove, as shown, between the vertical side sections.

The sections of the sides of the screen-frame are formed on their ends with tongues 85 21, one pair overlapping the adjacent pair on the ends of the adjoining side sections when the parts of all of the sides are fastened together.

Each corner of the frame has angle-sections E and F, which overlap the tongues and ends of the sections of the sides. Each angle-section is formed with ribs 22, which correspond and lap over the ribs and engage the tongues on the sections of the sides. 90

The resilient strips 10 extend to the ends of the side sections, as indicated by the dotted lines 23, and do not overlap. By this mode of construction the frame is made strong and rigid, and the screen-meshing is clamped securely and held taut in the frame. 95

In constructing my invention the parts are assembled as follows: The sections 3 of the sides are placed on the corner-piece E, as shown in Fig. 5; the screen-netting 11 is laid 100 upon these parts, as shown in Fig. 6; the front sections 2 of the sides are then placed over the side and corner sections and screen-netting, as shown in Fig. 7, and, finally, the front corner-section F is laid over all of the sec- 105 110

tions and screen-netting, as shown in Fig. 1, and the parts are clamped together by means of the screws 12 and nuts 14.

Fig. 1 shows one half of a window-screen 5 and casing. The other half is of similar construction throughout.

It is obvious that the construction of the parts above described may be varied without departing from the principles which I have 10 applied, and I do not wish to confine myself to the exact construction specified.

In the alternate construction the tongue 16 is formed with offsets 24, which form resilient connections with the flanges 8 and 9 to retard 15 the sliding movement of the frame.

Having described my invention, what I claim as new, and desire to protect by Letters Patent, is—

1. A window-screen having a frame made 20 from thin metal, the sides and corners of which have overlying sections, said sections comprising longitudinal intermeshing ribs and grooves and flanges on their inner and outer edges and said corner-sections lapping 25 over the ends of said side sections, screen-netting between said inner flanges and ribs, and means for fastening said sections together.
2. A window-screen, consisting of a frame made from thin metal, the sides and corners 30 of which have overlying sections comprising longitudinal intermeshing ribs and grooves and flanges on their inner and outer edges, said corner-sections engaging said side sections, material between all of said sections to 35 be held in said frame, and means for clamping said sections to engage said material.

3. A device of the class set forth, consisting of a frame made from thin metal, the sides and corners of which have overlying sections, 40 said sections comprising longitudinal intermeshing ribs and grooves and flanges on their inner and outer edges, said corner-sections engaging said side sections, material between said sections to be held in said frame, and 45 means for clamping said sections to engage said material, said flanges on said outer edges being separated to form a groove, for the purposes specified.

4. A device of the class set forth, consisting 50 of a frame made from thin metal, the sides and corners of which are formed by overlying sections, said sections comprising longitudinal ribs and grooves and flanges on their inner and outer edges, said corner-sections lapping over said side sections, material 55 between said sections and passing between the flanges on said inner edges, means for clamping said sections together to hold said material, said flanges on the outer edges of said 60 sections being separated to form a guiding-groove, all in combination with a window-casing having a tongue in said guiding-groove on which said frame is adapted to slide.

5. A rectangular window-screen having its sides formed by front and back sections, the 65 ends of which overlap, said sections comprising longitudinal intermeshing ribs and grooves and flanges on their inner and outer edges, screen-netting between said front and back sections, corner-pieces having corresponding ribs lapping over the ends of said side sections, and means for clamping said sections together.

6. A window-screen having a rectangular frame, the sides and corners of which have two 75 overlying sections, said corner-sections lapping over the ends of said side sections, and all of said sides and corners comprising longitudinal intermeshing ribs and grooves and flanges on their inner and outer edges, screen-netting 80 between said sections, and means for clamping said sections together.

7. A device of the class set forth, consisting of a frame formed by a pair of overlying sections, having longitudinal intermeshing 85 ribs, flanges on the inner and outer edges of said sections, said outer flanges being separated to form a groove, material passing between said inner flanges in said ribs to be held in said frame, means for clamping said sections to hold said material, a window-casing, and a tongue on said window-easing in said groove, forming a resilient connection with the flanges at the sides of said groove.

8. A window-screen having a rectangular frame, the sides and corners of which have two overlying sections, said sections having tongues formed upon their ends which lap over each other, said sections comprising longitudinal intermeshing ribs and grooves and 100 having flanges on their inner and outer edges, screen-netting between said sections, means for clamping all of said sections and fastening said tongues to hold said screen-netting and the parts of said frame, a window-casing, 105 and tongues on said window-casing, said outer flanges and the tongues on said window-casing forming a spring engagement for holding said frame and permitting it to slide in said casing.

9. A window-screen having a frame, the 110 sides and corners of which have two overlying sections, said corner-sections lapping over the ends of said side sections and all of said side and corner sections comprising longitudinal intermeshing ribs and grooves and 115 flanges on the inner and outer edges, screen-netting between said sections, resilient strips between said ribs and netting, and means for clamping said sections together.

In testimony whereof I have signed my 120 name to this specification in the presence of two subscribing witnesses.
